UNITED STATES PATENT OFFICE.

JENNIE S. HETTINGER, OF CAMDEN, NEW JERSEY.

SHEET-PACKING.

1,068,585.

Specification of Letters Patent.

Patented July 29, 1913.

Application filed August 27, 1912. Serial No. 717,288.

To all whom it may concern:

Be it known that I, JENNIE S. HETTINGER, a citizen of the United States, residing at Camden, in the county of Camden and State of New Jersey, have invented certain new and useful Improvements in Sheet-Packing, of which the following is a specification.

My invention relates to improvements in sheet packing, the object of the invention being to provide a combined metal and fibrous packing which may be cut in various shapes and sizes, and which will be elastic and efficiently perform the function for which it is intended.

A further object is to provide a sheet packing which may be manufactured and sold at a reasonably low price, and from which perforated gaskets and other forms of packing may be cut.

With these and other objects in view, the invention consists in certain novel features of construction and combinations and arrangements of parts as will be more fully hereinafter described and pointed out in the claims.

In the accompanying drawings: Figure 1 is a plan view of the metal plate constituting a part of my improved packing showing the same in shape to receive the fibrous packing. Fig. 2 is a view in section on the line 2-2 of Fig. 1. Fig. 3 is a similar view in section showing the packing with its fibrous filling and in its final shape ready for the market, and Fig. 4 is a view similar to Fig. 3 illustrating a modification.

In forming my improved packing I first shape a thin plate of sheet metal 1 so as to form pockets 2 in opposite faces thereof. This can be accomplished by passing the sheet between suitable die rolls and I have illustrated the sheet as having the pockets of general diamond shape with the walls at an angle to the edges of the sheet. The invention is, of course, not limited to the shape or size of these pockets as they may be of various shapes and various depths, but they are preferably of such a depth that they ac-

commodate considerable fibrous packing 3. This fibrous packing is of asbestos or other similar material, and is located in the pockets in both faces of the sheet, and when the sheet is compressed, the walls 4 of the pockets are bent at an angle to the bottoms of the pockets as seen most clearly in Fig. 3. By thus bending the walls of the pockets, I not only form an efficient lock for the fibrous packing, but I also provide an elastic connection between the bottom wall of one pocket and the bottom walls of the adjacent pockets so that the packing is free to compress and expand, at the same time embodying inherent elasticity sufficient to overcome considerable pressures. If desired, I may cut out the bottoms of the pockets as seen in Fig. 4, so that the fibrous packing constitutes the entire surface at both sides of the sheet except where the division walls come.

I do not limit myself to the particular metal nor to the particular fibrous packing which are combined as above set forth, nor do I confine my invention to the other details of construction, but consider myself at liberty to make such changes and alterations as fairly fall within the spirit and scope of the appended claims.

Having thus described my invention, what I claim as new and desire to secure by Letters Patent is:

1. A sheet packing comprising bent metal sheet forming pockets, and fibrous packing in the pockets, substantially as described.

2. A sheet packing comprising a bent metal sheet having fibrous material embedded in the surface thereof, substantially as described.

3. A sheet packing comprising a bent metal sheet having pockets in its opposite faces, and fibrous material in said pockets, substantially as described.

4. A sheet packing comprising a bent metal sheet having fiber containing pockets therein, and the walls of said pockets bent at an angle to the surfaces of the packing of the sheet, substantially as described.

5. A sheet packing comprising a bent

sheet of metal having pockets formed in its opposite faces, fibrous material in said pockets, and the walls of said pockets bent at an angle to the surface of the packing, substantially as described.

6. A sheet packing comprising a section of sheet metal bent forming pockets in both faces of the sheet, said pockets separated from each other, and fibrous packing in said

pockets lying flush with the surfaces of the metal sheet, substantially as described.

In testimony whereof I have signed my name to this specification in the presence of two subscribing witnesses.

JENNIE S. HETTINGER.
